UNITED STATES PATENT OFFICE

169,920

BARBER CHAIR APRON

Victor J. Vece, Redwood City, Calif.

Application January 8, 1953, Serial No. 23,073

Term of patent 14 years

(CL. D3—26)

To all whom it may concern:

Be it known that I, Victor J. Vece, a citizen of the United States, residing at Redwood City, in the county of San Mateo and State of California, have invented a new, original, and ornamental Design for a Barber Chair Apron, of which the following is a specification, reference being had to the accompanying drawing, forming part thereof.

The single drawing figure is a plan view of a barber chair apron, showing my new design.

I claim:

The ornamental design for a barber chair apron, as shown.

VICTOR J. VECE.
